SPOON COVER

Gilbert E. Franzen, Garden Grove, Calif.

Application March 15, 1949, Serial No. 81,571

3 Claims. (Cl. 229—43)

1

My invention relates generally to covers or lids for food containers and more particularly to a cover which has an integral element thereon adapted to become a spoon bowl upon removal from the container, and form with the cover a convenient spoon.

Such a device is especially useful in the marketing of individual portions of ice cream or similar products. Heretofore, a separate spoon has been supplied for use in eating the food product, and in addition to the expense of the service, the handling of these easily lost and contaminated articles is a great inconvenience to the vendor.

By combining the cover and spoon two major improvements are made; the unit cost of the product is reduced, and a better service to the consumer is provided. Accordingly, a practical solution has long been sought and many such devices have been proposed. No commercially successful device has ever been provided, and the failure of those proposed can be attributed to the fact that they do not form a practical or desirable spoon.

In order to be useful the device must meet several inharmonious requirements. As a cover, the device must function to adequately seal the contents of the package, and for this purpose the desired shape is often a flat circular disk. When formed as a spoon the device should have the general shape of a conventional spoon including a bowl and a handle, since if it merely forms an oversize scoop, or a shapeless paddle it will not be a proper or desirable utensil for eating. During its use the spoon must have sufficient rigidity to withstand the bending stresses imposed upon it, and because it is often used to remove hard frozen products, the leading or cutting edge thereof should be properly shaped so that excessive manual force need not be applied. A mandatory requirement is that the contact surfaces be delivered in a clean and sterile condition to the consumer, and it is further desirable that in the formation and use of the spoon, the fingers of the user should not become soiled by contact with the wet surfaces of the cover. Still other factors are important, as a design which will permit the use of a low cost paper material and be adapted to simple mass production methods, and it is apparent that if these and other requirements are not met, the device will fail to be a practical spoon.

Accordingly, it is the major object of my invention to provide a device which meets the requirements of both a cover and spoon by its new and novel combination and arrangement of elements.

2

Another object of my invention is to provide a combination cover and spoon having great resistance to bending stresses because of its unique design and construction.

It is a further object of my invention to provide a device which may be easily transformed from a cover to a spoon without complicated directions or folding.

Still another object of my invention is to provide a device which is adapted to be modified into many different shapes and sizes to fit a variety of packaging needs.

A still further object of my invention is to provide a combined cover and spoon which is delivered to the consumer with the bowl portion thereof in an absolutely clean and sterile condition.

These and other objects and advantages of my invention will become apparent from the following description of preferred and modified forms thereof, and from an inspection of the accompanying drawings in which:

Fig. 1 is a perspective view of a preferred form of my invention shown in place as a closure for a food container;

Fig. 2 is a plan view of the inner face of the device showing the scoring lines thereon;

Fig. 3 is a cross-section taken along the line 3—3 of Fig. 2;

Fig. 4 is a side elevation of the device in its operative position as a spoon;

Fig. 5 is a perspective view of the device showing the manner in which it is held in the hand of the user;

Fig. 6 is a partial plan view of an optional form of the device; and

Fig. 7 is a partial plan view of another modified form of the device.

Referring now to the drawings and particularly to Fig. 1 thereof, the numeral 10 indicates a food container or cup of generally cylindrical shape. The cup 10 may be of any desired shape or size and forms no part of my invention, the illustrated shape merely being one which is conventional and widely used in the art. A cover 11 has a body member formed as a lid or circular disk 12 to engage with the inner cylindrical wall of the cup 10 and form a closure, preventing loss or contamination of the food product therein. On an edge of the disk 12 is a projecting element 13 which is adapted to form a spoonbowl, and at an opposed position on the circumference of the disk is a small projecting tab 14. When the lid member 12 is placed in the cup 10, the element 13 is folded downwardly into the interior of the cup, and the tab 14 is folded upwardly as is best seen in Fig. 1. In this position, both the element 13

and the tab 14 are folded along the normal edge or perimeter of the lid 12 to allow the latter to conform to the wall of the cup 10 for sealing engagement therewith. To permit positive and even displacement of the element 13, a score line 17 is provided inwardly of the element along the normal perimeter of the lid 12, as will be described hereinafter. It can thus be seen that the cover 11 adequately performs its function as a closure in a manner similar to a conventional cover, there being no interference because of the element 13. It should also be noted that before the removal of the cover 11 the entire element 13 is sealed within the interior of the cup 10, and thus remains in a clean and sanitary condition.

When the tab 14 is grasped and pulled, the body or lid 12 pivots upwardly about the score line 17 and element 13 until it is in a generally vertical position. If the food product in the cup 10 is in a solid or frozen state, it will resist movement of the element 13 embedded therein until the lid 12 is vertical. At this time, a slight additional upward pull on the tab 14 will be sufficient to dislodge the element 13 which now slides free without removing any of the food product.

From the vertical position, the cover 11 is further rotated about a horizontal axis until it is in an inverted position and the inner face of the disk 12 (lower face in Fig. 1) becomes the upper face of the disk as seen in Figs. 2, 4 and 5. This face of the disk 12, as may best be seen in Fig. 2, has converging score lines 15 and 16 extending inwardly from the corner junctions of the element 13 with the perimeter of the disk to form a triangular sector 18 bounded outwardly by the score line 17 which is an arc or chord along the perimeter of the lid. From the vertex formed by the score lines 15 and 16 a single score line 19 extends diametrically across the disk 12 to divide the remaining area of the disk into two equal sectors 20 and 21. It is preferable that the tab 14 should not be at the extremity of the score line 19, and it is therefore offset slightly, the exact position being immaterial so long as it remains generally opposite to the element 13.

All of the score lines may be formed very simply as a stamping operation during the manufacture of the cover 11, the material of the cover being one of low cost which is impressionable, such as a heavy paper. It is desirable that the grain of the material extend longitudinally parallel with the score line 19, and many suitable types of material can be used. As is seen in Fig. 3, the score lines should be of sufficient depth to allow easy unidirectional deflection of the elements, but the exact depth and shape thereof will depend upon the material selected.

After the cover 11 has been inverted the sectors 20 and 21 are folded together along the score line 19 and the converging score lines 15 and 16, as is best seen in Fig. 5. Since the score lines are on the inner face of the disk 12 they allow inward deflection but resist deflection in the other direction. Hence, formation of the device is very simple, and tests have shown that without any instructions, the user will readily grasp the principle involved and fold the sectors 20 and 21 properly.

After the one step of folding, the device is transformed into a spoon, the sectors 20 and 21 forming a handle, while the element 13 forms a spoonbowl. Because of their spaced relationship, the outer extremities of the lines 15 and 16 are drawn upwardly, thereby inducing an upward conical curvature in the triangular sector 18 and

the projecting element 13. As is best seen in Figs. 4 and 5, the sector 18 and the element 13 are deflected upwardly from the central score line 19, and the sharp corner folds of the material along the score lines 15 and 16 act as spreaders to keep the mouth of the element 13 open and flat enough to form a desirable bowl shape. The stresses acting along the score lines 15 and 16 are a function of the vertex angle of the triangular sector 18 and should be sufficient to cause a substantial arching of the sector 18 and element 13. It has been found that the vertex angle indicated at 22 should normally be approximately 60° for the best operation of the device. If the angle 22 is materially larger, the resulting stresses may cause a failure of the material, and if the angle 22 is much smaller, the element 13 will not have a desirable bowl shape. It should be noted that the outer shape of the sectors 20 and 21 does not affect the transformation of the cover 11 in any way. Accordingly, the cover 11 may be made in many different shapes and sizes without changing the practicability of the spoon.

The curvature induced in the triangular sector 18 and the element 13 gives the device great resistance to bending stresses while in operation. As seen in Fig. 5, the fingers of the user hold the sectors 20 and 21 together while the element 13 is dipped into the food product packed in the cup 10. Because of its generally cylindrical curvature, the element 13 strongly resists either upward or downward deflection, and may therefore be used to dig or scoop the food product exactly the same way as can be done with a conventional metal spoon. In the form shown in Fig. 5, the score line 17 is arched both outwardly and upwardly to prevent any upward deflection of the element 13 therewith. Since the score line 17 is on the upper surface of the disk 12, it is almost impossible to deflect the element 13 downwardly, and thus the largest stresses created by a scooping movement of the device are most strongly resisted.

The element 13 has a rounded forward edge 23 to form a cutting surface, and in the preferred form is shaped quite similar to a conventional spoon bowl. Other shapes of the edge 23 may be used as desired, as for example the edge may be serrated to provide a series of prongs or tines to allow the device to be used as a fork so long as the basic structural characteristics of the device are maintained.

In Fig. 6 is shown an optional form of the device to be used when it is desired that the element 13 project from a side of a lid 12 bounded by straight edges. A straight score line 17a bounds the outer edge of the triangular sector 18 so that the latter may conform to the normal perimeter of the lid 12. The other score lines 15, 16, and 19 are the same as those used in the preferred form and the operation of the device is identical. The use of an outwardly curved score line 17 is preferred to the score line 17a since it helps to resist upward deflection of the element 13. However, in any form of the device the element 13 and sector 18 are conically curved so that deflection is resisted either upwardly or downwardly, and tests have shown that the form using the score line 17a is sufficiently rigid for all practical uses.

In Fig. 7 is shown another modified form of the device to be used when it is desired that the element 13 project from a corner of a generally polygonal lid 12. Two angled score lines 17b and 17c bound the outer edge of a sector 18a which

is quadrilateral in shape and corresponds to the triangular sector 18. The angle between the score lines 17b and 17c is the regular interior angle of the polygonal lid 12, and thus the sector 18a conforms to the normal perimeter of the lid 12 and in no way interferes with the use of the lid as a closure. The other score lines 15, 16, and 19 are the same as those used in the preferred form and the operation of the device is identical. The outwardly angled score lines 17b and 17c 10 tend to resist upward deflection of the element 13 as does the curved score line 17 in the preferred form, and again the major resistance to either upward or downward deflection is provided by the conical curvature induced into the element 13 and sector 18a.

The form of the device to be used depends, of course, upon the shape of the lid 12 and the container 10. All of the forms embody the advantages of simplicity, rigidity, and ease of formation as previously set forth. Again, it should be noted that the device is delivered to the user in a clean and sanitary condition. The entire element 13 and the interior face of the disk 12 are sealed within the cup, and thus there is no chance of contamination.

While I have shown and described in some detail the preferred embodiment of my invention, it is to be understood that such details are not restrictive and that various changes in design and construction may be made without departing from the scope of my invention as defined in the appended claims.

I claim:

1. A cover for use with a food container comprising: a flat cover member having a contour for edge engagement with said container; score lines on the inner face of said cover member converging inwardly from the edge of said member to form a triangular sector; a single score line extending across the inner face of said cover member from the vertex of said converging lines to cooperate therewith and facilitate an inward folding of said member to form a handle; a transverse score line on said cover member extending between the spaced ends of said convergent score lines; and an integral acutely curved element extending from the edge of said cover member between the spaced ends of said convergent score lines, and inwardly defined by said transverse score line, said element being deflectible from the plane of said member along said transverse score line to a displaced position disposing said element entirely within said container, said element being movable from said displaced position to an operating position substantially aligned with the initial plane of said score lines in response to folding of said member to form a handle, and said element having a curvature induced thereacross by said folding to resist deflection from said operating position.

2. A cover for use with a food container comprising: a flat cover member of deformable material having a contour for edge engagement with said container; score lines on the inner face of said cover member converging inwardly from the edge of said member to form a triangular sector; a single score line extending across the inner face of said cover member from the vertex of said converging lines to cooperate therewith and facilitate an inward folding of said member to form a handle with said member being forced out-

wardly along said converging score lines and deformed sharply therearound to induce a conical curvature in said triangular sector; a transverse score line on said cover member extending between the spaced ends of said convergent score lines; and an integral element extending from the edge of said cover member between the spaced ends of said convergent score lines, and inwardly defined by said transverse score line, said element having the outline of a spoonbowl, and being deflectible from the plane of said member along said transverse score line to a displaced position disposing said element entirely within said container, said element being movable from said displaced position to an operating position substantially aligned with the initial plane of said score lines in response to folding of said member to form a handle, and said element having a bowl-like curvature induced therein by said folding to resist deflection from said operating position and form a suitable eating implement.

3. A cover for use with a food container comprising: a disk member of deformable material having a contour for edge engagement with said container; score lines on the inner face of said disk member converging inwardly from the edge of said member to form a triangular sector; a single score line extending across the inner face of said disk member from the vertex of said converging lines to cooperate therewith and facilitate an inward folding of said member to form a handle with said member being forced outwardly along said converging score lines and deformed sharply therearound to induce a conical curvature in said triangular sector; a transverse score line on said disk member extending between the spaced ends of said convergent score lines and conforming to the normal contour of said disk member; an integral element extending from the edge of said disk member between the spaced ends of said convergent score lines, and inwardly defined by said transverse score line, said element having the outline of a spoonbowl, and being deflectible from the plane of said member along said transverse score line to a displaced position disposing said element entirely within said container, said element being movable from said displaced position to an operating position substantially aligned with the initial plane of said score lines in response to folding of said member to form a handle, and said element having a bowl-like curvature induced therein by said folding to resist deflection from said operating position and form a suitable eating implement; and a small projecting tab on said disk member spaced generally opposite to said element and deflectible from the plane of said member to an exposed position in which said tab may be readily grasped to remove said member from said container.
